3 Claims. (Cl. 201—48)

1

This invention has to do with means for developing an electrical voltage or current that corresponds in a definite manner to the mechanical movement of an element, such, for example, as the sensitive element of a measuring instrument. Such an electrical representation of a mechanical movement may be utilized typically for controlling a circuit in accordance with the movement, and for indicating at a distance, as by an electrical instrument, the instant position of the movable element.

Previously available devices for translating a mechanical movement into a corresponding electrical variable commonly utilize a resistance coil and a brush that is movable along the coil in response to the mechanical movement to be represented. Such devices are of limited usefulness, particularly in connection with instruments in which the sensitive element has relatively short travel. Not only is it difficult in many instances to obtain a sufficient range of effective electrical resistance with the brush movement available, but it is often impossible to provide enough coil turns in the resistance coil to give the desired smoothness of response. Mechanical amplification of the available travel, as by a linkage, has the serious disadvantage of correspondingly amplifying the load imposed upon the movable element.

An important object of the present invention is to overcome such difficulties, and thereby to provide means for developing a voltage or current that varies substantially smoothly in definite correspondence with linear movement of an element, even though the travel of that element be very small. Moreover, the invention accomplishes that result without imposing upon the moving element any appreciable additional load.

That is accomplished typically in accordance with the invention by mounting a resistance coil and its cooperating brush in such a way that the relative movement of coil and brush, in response to movement of the movable element to be represented, is not parallel to the axis of the coil, but is oblique thereto. That is made possible by providing a novel type of brush, which has an elongated contact surface.

The invention further provides, in its preferred form, a coil structure that includes a longitudinal contact edge that is relatively sharp in transverse section, the wire of each coil turn making a relatively sharp bend as it passes the contact edge of the coil.

A further object of the invention is the provision of a special mounting for the coil and

2

brush which maintains the necessary spatial relationship between them while permitting relative adjustments of special types.

A full understanding of the invention and of its further objects and advantages will be had from the following description of certain embodiments of it in instruments of illustrative types. That description and the accompanying drawings, which form a part of it, are intended only as illustrations, and not as limitations upon the scope of the invention.

In the drawings:

Fig. 1 is a section of an illustrative embodiment of the invention, taken on line 1—1 of Fig. 3;

Fig. 2 is a section on line 2—2 of Fig. 1;

Fig. 3 is a section on line 3—3 of Fig. 1;

Fig. 4 is a section on line 4—4 of Fig. 1;

Fig. 5 is a fragmentary section on line 5—5 of Fig. 1, shown at enlarged scale;

Fig. 6 is a longitudinal section of another illustrative embodiment of the invention, taken on line 6—6 of Fig. 8;

Fig. 7 is a transverse section on line 7—7 of Fig. 6;

Fig. 8 is a transverse section on line 8—8 of Fig. 6;

Fig. 9 is a side elevation of another illustrative embodiment of the invention; and

Fig. 10 is a plan corresponding to Fig. 9.

Figs. 1—5 represent an illustrative embodiment of the invention in an instrument for developing a voltage corresponding to the difference between two fluid pressures. The instrument comprises a pressure sensitive element, shown as a metal bellows 20, the movement of which in response to changes of fluid pressure differential is caused to develop a corresponding voltage by movement of the brush 22 over potentiometer coil 50. The instrument is housed in a case which comprises typically three principal sections. The generally cylindrical case body 30 is closed at one end by the flexible diaphragm 32 and cover plate 34 and at the other end by the bellows housing 36. All moving parts of the instrument are supported as a movement assembly 40 on the circular mounting plate 42, apertured at 44, which is rigidly clamped, as by the screws 41, between case body 30 and bellows housing 36. The junctions between those two case members and between each of them and mounting plate 42 are sealed by a single O-ring 38, while diaphragm 32 effectively seals cover plate 34 to the case body. Upon removal of screws 41 and bellows housing 36, the entire movement assembly 40 is immediately bodily removable from the case,

rendering the parts to be described readily accessible, as for adjustment.

The inner end of bellows 20 is open, and is edge mounted upon the outer face of mounting plate 42, to which it is soldered or otherwise secured in fluid-tight fashion, surrounding plate aperture 44. The outer end of the bellows, which is free, is closed in the usual manner by a cap 46 which carries on its inner face a rigid post 48 extending internally along the axis 21 of the bellows to a point inward of plate 42. The inner end of post 48 carries brush 22, which thus moves, relatively to plate 42, along the axis 21 of bellows 20 as the latter expands or contracts.

The contact edge 24 of brush 22 comprises an elongated cylindrical surface of relatively sharp curvature. That surface is tangent to a plane 23 that is parallel to the brush movement, that is, parallel to bellows axis 21. Plane 23, which will be referred to as the contact plane, preferably passes approximately through axis 21, and may be visualized as being normal to the planes of Figs. 2, 4 and 5 at the lines 23. The line in which the relatively sharp contact edge of the brush is tangent to contact plane 23 is preferably straight, and as illustrated is substantially normal to bellows axis 21.

Contact edge 24 of brush 22 is preferably so mounted on post 48 as to be substantially rigid with respect to movement parallel to contact plane 23, but to be capable of yielding movement normal to that plane. A preferred manner of construction by which that may be attained is shown illustratively in the figures and comprises a mounting bar 25, rigidly mounted transversely of post 48 and insulated therefrom as by a sheet 28 of dielectric material, and a leaf spring 26, having one edge rigidly mounted longitudinally of bar 25 and extending therefrom in a flat curve generally parallel to contact plane 23. The free edge of spring 26 is stiffened as by a flange 27, which may be, and preferably is, integral with the spring. The brush contact surface 24 is parallel to flange 27, and may comprise a fine wire 24a of a suitable noble metal secured rigidly to the flange at its junction with the spring body. A wire somewhat longer than the contact surface to be formed is preferably stretched taut between suitable jaws and brought into parallel relation adjacent the elbow of the spring flange, and solder is then flowed between the wire and the spring and allowed to harden as at 29, fixedly mounting the wire as a strictly rectilinear contact edge of smoothly and uniformly rounded section. The radius of curvature of that contact surface is readily controllable by selection of the wire diameter, which may typically be five to twelve thousandths of an inch. The brush may be electrically connected, as by a light and flexible wire lead 64 to a brush terminal 65 which extends through and is insulated from the wall of case body 30.

The pressure to be represented is admitted to the chamber 37, surrounding bellows 20 and between mounting plate 42 and bellows housing 36, through a suitable port in that housing, shown typically at 37a with threads for connection of a pressure line. A reference pressure may be similarly admitted through port 31a to the chamber 31 between cover plate 34 and flexible diaphragm 32. The entire space 33 between diaphragm 32 and mounting plate 42, including also the interior of bellows 20 is preferably filled with a chemically inert, substantially incompressible fluid, as through a port provided for that pur-

pose in the wall of case body 30. Such a port is shown in Fig. 1 sealed by the screw plug 35. The reference pressure in chamber 31 is then transmitted to the interior of bellows 20, and the position of brush 22 longitudinally of bellows axis 5 as is determined by the differential between the pressure in chamber 31 and that reference.

Potentiometer coil 50, as shown, is of flat section and is longitudinally tapered, as shown best in Fig. 4. The coil has a longitudinal contact edge 52 which is preferably accurately straight and sharp in a sense to be further explained. The coil is mounted on plate 42, on the opposite face of the plate from bellows 20. The illustrative mounting means shown includes a fixed bracket 54, which may be rigidly mounted on plate 42 as by soldering. Bracket 54 includes a plate-like body portion 55 which lies in a plane normal to mounting plate 42 and parallel to the working edge of brush 22, and which is provided with a track parallel to the movement axis 21 of bellows 20. That track is represented in the present embodiment by the slot 56 in the plate-like body of the bracket. A flat slide member 60 is supported on, and in parallel relation to, bracket 54 for adjustable movement in translation in its own plane longitudinally of slide 56. As illustrated, two threaded studs 61 are fixed in slide member 60 and are slidably received by slot 56, the nuts 62 being turned down on the studs to clamp bracket 54 in adjusted position between one face of slide 60 and a clamping washer 63.

A swinging bracket 70 has a flat base portion 71 and a plate-like arm portion 72 forming a right angle with the base. Bracket base 71 lies flatly against the opposite face of slide member 60, and is adjustably swingable through an angle of about 30° in the plane of that face about an axis defined by pivot stud 73, fixed in bracket base 71 normal to movement axis 21. A parallel locking stud 74 is received by a curved slot 67 in slide member 60, permitting convenient locking of the swinging movement of bracket 70 by tightening of the nuts 75 and 76 on the respective studs 73 and 74. Arm portion 72 of bracket 70 carries a track, shown as two parallel slots 78, parallel to the pivot axis about which the bracket is adjustable.

A mounting block 80 is mounted on bracket 70 in a manner to be adjustable in translation along track 78 and also in rotation through a small angle about an axis normal to the track. Such dual adjustability of block 80 may be guided and clamped, for example, by the two screws 82, threaded into a flat face of the block and received with adequate clearance in the respective slots 78. To facilitate relative adjustment of the block and bracket when screws 82 are loose, adjusting screws 84 may be provided, screw-threaded into ears 77 of bracket 70 parallel to track 78 and freely received in bores in block 80. Springs 85 hold the block against the heads of screws 84.

Resistance coil 50 is fixedly mounted, as by the screws 81, against the face of block 80 opposite to bracket arm 72, with the contact edge 52 of the coil parallel with bracket base 71 and facing toward it. The flat coil thus lies in a plane parallel to the axis of pivot stud 73, and the parts are preferably so proportioned that the axis of pivot stud 73 passes through the contact edge 52 of the coil close to one end of its effective length. The parts described are also so proportioned that contact edge 52 of the resistance coil is approximately tangent to contact plane

23, opposing the described contact edge 24 of brush 22, with which it makes electrical contact. The exact relative positions of the coil and brush are so adjusted by the screws 84, already described, that contact of the surfaces slightly deforms leaf spring 26, producing a light yielding contact that is substantially uniform regardless of the longitudinal position on the coil of the point of contact. The opposite ends of resistance coil 50 are electrically connected, as by flexible leads 66 and 67, to the two coil terminals 68 and 69, set in case body 30 and extending through its wall in insulated relation.

The rotational position of coil 50 and bracket 70 about pivot stud 73 is adjusted to give the desired angle b between the length of coil 50 and brush 22, as seen, for example, in Fig. 1. The approximate value of that angle, for the present illustrative embodiment in which brush 22 is approximately normal to the direction of brush movement, is such that the sine of angle b equals the ratio of the maximum travel of brush 33 to the usable length of coil 50. In accordance with the invention, that ratio is appreciably less than unity, and may be as small as 0.2 or less. In other words, although the total travel of the movable element (here represented by the free end of bellows 20) may be relatively small, the usable length of resistance coil 50 over which brush contact edge 24 moves may be relatively great. That is in marked contrast to previous devices, in which the range of movement of the potentiometer brush along the coil is no greater than the available travel of the movable element to be portrayed.

For example, if the total brush travel between the highest and the lowest anticipated pressures is 0.02", that distance is also the maximum usable length of the resistance coil in previously available instruments of the type here described. If the resistance coil is wound with wire of 0.001" diameter, no more than 20 turns can be provided within the usable length of such a coil, since the average lead of the coil must be at least equal to the wire diameter. That means that only 20 steps are available by which to represent the smoothly varying pressure, leading necessarily to a relatively crude approximation. That cannot well be remedied merely by magnifying the mechanical movement by a linkage, since the force required of the instrument to move the brush over the coil is thereby magnified at least in the same ratio, leading in practice to uneven and unreliable response.

The difficulty is solved in the present embodiment of the invention by setting the resistance coil at a relatively small angle b with the elongated brush. If that angle is 11.5°, for example, so that $\sin b$ is about 0.2, then the usable length of the coil is five times greater than the linear travel of the brush. Thus, with a brush travel of 0.02", the point of contact with the coil moves over a range of 0.10" on the coil. That coil length may include typically about 100 turns, providing satisfactorily smooth electrical representation of the brush movement. Moreover, the force required of the bellows to move the brush is not increased by such oblique position of the coil.

The exact degree of effective amplification of the brush movement is very conveniently adjustable by variation of angle b , which is accomplished by release of nuts 75, 76 and rotation of bracket 70 about the axis of stud 73. The coil may be adjusted bodily longitudinally of bellows

axis 21 by releasing nuts 62 and moving slide member 60 along track 56 in fixed bracket 54. By that adjustment the brush contact point may be brought to any desired zero position on the coil contact surface for a definite selected pressure differential. That zero point is preferably taken at the intersection of the axis of pivot stud 73 with the coil contact surface. The coil can then be rotated about that axis to adjust angle b without disturbing the zero adjustment.

A preferred manner of forming the contact surface of a resistance coil in accordance with the invention is shown best in Fig. 5. The coil form 51 is preferably of flat section, as indicated, and made of insulative material. One longitudinal edge of the coil form is tapered as indicated at 53. That taper may be carried to a relatively sharp edge, and the wire of the coil may be wound directly over that edge. However, in the preferred embodiment illustrated, the taper leaves a thin flat edge, which is slotted to receive a relatively thin insert 57. The exposed edge of insert 57 is smoothly rounded in section, and is accurately straight in a direction longitudinal of the coil. Such an insert is preferably of a relatively hard dielectric material that can be accurately worked. Glass has been found to be a suitable material. The wire with which the coil is wound passes over insert 57. The thickness of the insert and the shape of its exposed longitudinal edge and also the tapered form 53 of the coil form proper are so chosen that the coil wire bends sharply as it passes over the edge of the insert. That bend is quite sharp, even in proportion to the relatively small diameter of the wire. For example, the radius of curvature of the wire at the point of maximum curvature is preferably only 2 to 7 times the diameter of the wire itself, which may typically be about one mil. That relatively sharp curvature of each wire turn at the contact surface of the coil, combined with the relatively sharp contact edge 24 of the brush, permits the angle b between coil and brush to be made quite small without causing such irregularities of contact as simultaneous contact of the brush with more than two turns, or with non-adjacent turns, of the coil.

Figs. 6-8 show another illustrative embodiment of the invention, comprising a feeler gage adapted for translating small movements of the feeler head into corresponding electrical voltages. As illustrated, the instrument is mounted in a cage having a tubular body portion 90 and forward and rear caps 91 and 92 closing the respective ends of the tube. A lever 94 is mounted longitudinally within the case body for pivotal movement about a pivot axis 95 transverse of the case near its forward end. In the preferred embodiment shown, that mounting comprises two pairs of crossed leaf springs 96 opposite ends of which are secured to block 97 and to cross arm 98, extending transversely from lever 94 parallel to pivot axis 95. That axis is a line that passes through all four springs. The swinging movement of lever 94 about axis 95 may be limited by abutment stops adjustably mounted with respect to case body 90. Such abutments are indicated typically as screws 105 radially threaded in fixed brackets 107 and accessible for adjustment through access apertures 109 in the case body. Springs 96 establish an equilibrium, or zero, position of lever 94, which may be substantially midway between abutment stops 105, or may be relatively close to one of the stops. The lever is resiliently swingable from that

equilibrium position in response to a relatively slight torque.

Lever 94 projects forwardly from pivot axis 95 through a clearance aperture 93 in forward cap 91, and carries at its forward end a spherical feeler head 99. The lever extends rearwardly from pivot axis 95 along the cylindrical axis of the case and carries at its rearward end a brush 100. That brush may be constructed in a manner similar to that already described for brush 22 of the embodiment of Figs. 1-5, but as shown is of a somewhat different type. A leaf spring 102 of Y form is mounted on lever 94 with its arms 103 extending generally parallel to each other on opposite sides of the longitudinal axis of lever 94 and in a plane approximately normal to that axis. A wire 104 extends between the ends of the two spring arms, and is stiff enough in relation to the flexibility of the spring arms that it may be considered for all practical purposes to be a straight rigid rod. As illustrated, that rod, which forms the contact edge of brush 100, is parallel to pivot axis 95. Brush 100 is preferably electrically insulated from lever 94 on which it is mounted, and is connected, as by a relatively fine and flexible insulated wire 106 to a pin of an electrical connector 108, which is mounted in the case wall, for example in the wall of rear cap 92.

A resistance coil 110 is supported as by a bracket on the inner face of rear cap 92. The coil axis is normal to the longitudinal axis of the case and oblique with respect to pivot axis 95 and to brush 100. Coil 110, as shown, is of irregular section with a relatively sharp contact edge 112 directed toward brush 100. The plane tangent to the brush and coil at their point of contact is normal to the longitudinal axis of case body 90 and is parallel to pivot axis 95. That contact plane is indicated by the line 115 in Fig. 6. The illustrated brush structure is typical of a great variety of detailed structures, in that it produces relatively great flexibility of the brush in a direction normal to contact plane 115, and relatively great stiffness parallel to that plane. That results in a uniformly yielding contact with the coil, and yet maintains in full effect a definite and positive position of the brush relative to lever 94 in the direction of movement of that lever. Opposite ends of coil 110 are electrically connected to pins of connector 108 as by wires, one of which is indicated at 111.

The angle between contact edge 112 of the coil and brush 100 may be definitely fixed during assembly of the device, or may be adjustable, for example by rotation of cap 92 on case body 90, the adjusted position then preferably being locked by any suitable means such as a locking screw 114 which is slidably received in a circumferentially slotted hole in the cap flange. Other adjustments of the type described in connection with Figs. 1-5 may be provided, although for many purposes it is sufficient to rely upon accurate manufacture and assembly of the parts to give correct cooperation of brush and coil. That is particularly true if spring arms 103 are relatively flexible in a direction normal to contact plane 115. Such flexibility of the brush structure compensates, for example, for the fact that the movement of brush 100 is not strictly limited to translation, but includes a small component of rotation about pivot axis 95.

As illustrated, the length of the forward arm of lever 94, from pivot axis 95 to the center of head 99 is only about one quarter that of the

other arm, measured from axis 95 to contact plane 115. The ratio of those lengths may typically be 1:4. That has the effect of amplifying the resultant brush movement, responsive to a given displacement of head 99, by a factor of four. As already indicated, another effect of such leverage is to amplify the force required at head 99 to move brush 100 over coil 110 in opposition to the surface friction. For some purposes, of which the present instrument is illustrative, the load on the sensitive element need not be held to an absolute minimum, and a corresponding increase of load due to friction can be tolerated. However, even under such conditions, that increase is usually limited, and the amplification factor that is tolerable for the friction may still be insufficient to give the required range of brush movement. Moreover, the degree of amplification that can be obtained by means of a lever system is limited in practice by backlash and friction at the pivot when a conventional pivot bearing is used. In the spring type of pivot of the present embodiment, friction may be virtually eliminated. However, unless the angle of deflection is held within a limit of about 10°, an appreciable force is required to overcome the spring stiffness, and difficulties may be encountered from hysteresis effects. All of those difficulties, as well as the space requirements of a lever system, are most serious at relatively high lever ratios. At relatively low lever ratios the cited disadvantages may be limited to acceptable proportions.

In accordance with the present invention it is possible to obtain a relatively large effective amplification of the potentiometer brush movement without incurring the serious disadvantages of a lever system of corresponding ratio. That is done by combining a lever system of moderate ratio with suitable relative orientation of the brush and coil. By utilizing the amplifying effect of a small oblique angle between brush and coil, in combination with a lever system of moderate ratio, it becomes for the first time possible to obtain relatively great values of the overall amplification, while retaining high accuracy and sensitivity and relatively low loading of the sensitive element. It is found desirable to limit the leverage amplification to a factor between about two and about six, while it is practicable to make the overall amplification of the combination from about two to about six times that of the lever system alone. As an illustration, angle *b* as shown in Fig. 8, is approximately 19.5°, giving an effective 3-fold amplification of the brush movement. The overall amplification, with the combination of leverage system and coil angle shown, is therefore twelve. That is, movement of feeler head 99 through a distance of 0.001" normal to the longitudinal axis of the instrument and to pivot axis 95 displaces the electrical contact point of brush 100 along coil 110 by a distance of 0.012". That coil length may readily accommodate about 12 coil turns, so that the instrument can be counted on to respond to a movement of the sensitive element through only 0.0001".

Another illustrative embodiment of the invention is shown in Figs. 9 and 10. A curved Bourdon tube is represented generally by the numeral 130. The tube is mounted midway of its length upon a threaded fitting 131 by means of a short side tube 132 which provides a fluid pressure connection between fitting 131 and the interior of the Bourdon tube. An electrical resistance coil

140 is mounted bodily upon one of the free ends 134 of the Bourdon tube, and a cooperating brush 150 upon the other free end 135 of the tube. As the curvature of the Bourdon tube changes in response to changes of internal fluid pressure, altering the distance between its free ends, the brush is moved longitudinally of the coil.

An advantage of the type of instrument shown is in its inherent freedom from disturbance by vibration or by other types of acceleration to which it may be exposed. The two arms of the Bourdon tube are preferably at least roughly balanced dynamically. The counterweight 137 rigidly mounted on the brush end 135 of the tube represents illustrative means of substantially balancing the resonant periods of the two arms of the tube.

The particular mounting means illustrated in Figs. 9 and 10, although extremely simple, provides three distinct types of adjustment for the relative positions of coil and brush. Coil 140, as shown, is wound on a form 141 of insulative material. That form is of flat section and lies in a substantially vertical plane as seen in Fig. 9, that position of the instrument being purely illustrative. The coil is rigidly connected to a light frame 142, which is centrally mounted upon bracket 144, rigidly connected to end 135 of tube 130. The connection between frame 142 and bracket 144 permits rotational adjustment of the bracket with respect to the frame about an axis normal to the length of coil 140. As shown, that connection is the single screw 146, threaded vertically into bracket 144.

Brush 150, as shown, comprises a wire 152 stretched between the two arms 153 and 154 of a U-shaped mount of flat spring material 155. The body of mount 155 is slotted at 156 parallel to the axis of the U. The single screw 157, freely received in slot 156 and threaded vertically into the fixed bracket 158, secures mount 155 to bracket 158 in a manner permitting rotational adjustment of the brush about the vertical axis of screws 157 and also translational adjustment along the length of slot 156. The spring arms 153 and 154 are relatively flexible in a direction normal to their plane, providing yielding contact between brush 150 and the upper edge of coil 140. At the same time, the flexibility of the brush mounting is relatively slight in the plane of mount 155, so that the position of the brush is effectively positively defined in that plane with respect to end 135 of the Bourdon tube upon which it is mounted. Electrical connection may be made to the brush through fitting 131, and to the coil through insulated leads, not shown.

The angle b between coil and brush is shown illustratively in Fig. 10 as approximately 14.5°, giving substantially a four-fold amplification of the relative movement of the two ends of the Bourdon tube. It will be seen that such amplification is attained by extremely simple and economical means, and without destroying the advantages inherent in the illustrated type of instrument.

It will be understood that many alterations may be made in the specific embodiments described without departing from the spirit of the invention, and that those embodiments are not by any means intended to represent the only types of instrument in which the invention may have utility.

I claim:

1. In an instrument for comparing two fluid

pressures, the combination of two housing members essentially of cup shape, an apertured mounting plate, assembly means releasably securing the housing members in opposed relation on opposite sides of the mounting plate and in hermetically sealed relation therewith to form a generally cylindrical housing that is partially divided transversely into two chambers by the mounting plate, a generally cylindrical pressure responsive bellows closed at one end and open at the other end, the open end of the bellows being rigidly secured in hermetically sealed relation to the mounting plate, with the length of the bellows extending transversely thereof in one of the chambers and with the aperture in the mounting plate forming a passage between the other chamber and the interior of the bellows, structure forming passages for admitting fluid pressures to be compared to the said one chamber externally of the bellows and to the other chamber, respectively, an elongated brush support having one end rigidly mounted on the closed end of the bellows and extending longitudinally and internally thereof with its free end projecting in spaced relation through the aperture in the mounting plate into the other chamber, a potentiometer brush mounted on the free end of the brush support for movement therewith in a direction axially of the bellows in response to differences between the pressures to be compared, a potentiometer coil, bracket structure supported solely on the mounting plate and mounting the potentiometer coil in the other chamber in position to be engaged by the potentiometer brush, the length of the coil forming an acute angle with the said direction of movement of the brush, and the said bracket structure including means for adjustably varying that angle, release of the said assembly means providing full access to the bellows and to the said bracket structure while maintaining normal relationship of the potentiometer brush and coil.

2. In a potentiometer, in combination, a potentiometer coil comprising a coil form of relatively soft dielectric material having a flat transverse section and having a longitudinal edge that is approximately straight, a longitudinal slot in the form edge substantially midway between the flat form faces, an insert of relatively hard dielectric material mounted in the slot and having a longitudinal edge that extends beyond the form edge and that is accurately straight and of uniform predetermined transverse section, and a coil winding wound on the form, each turn of the winding passing over the exposed edge of the insert and taking a definite curvature corresponding to the transverse section thereof; a potentiometer brush having an elongated contact edge, and means supporting the brush for relative sliding movement with respect to the coil, the contact edge of the brush forming an acute angle with the length of the coil and engaging the winding where it passes over the insert.

3. A feeler gage comprising an elongated generally cylindrical housing having an aperture at one end and having the other end closed by a cap that is adjustably rotatable about the longitudinal axis of the housing, an elongated lever mounted intermediate its length within the housing for swinging movement about a pivot axis normal to the housing axis and adjacent the apertured end of the housing, one end of the lever extending through the said aperture and carrying an abutment at a relatively small radius from the pivot axis, two mutually engageable potenti-

ometer elements comprising respectively a potentiometer coil and brush, each of said elements having an elongated contact edge, means mounting one potentiometer element on the inner face of the housing cap with its contact edge in a plane normal to the housing axis, means mounting the other potentiometer element on the other end of the lever with its contact edge extending longitudinally of the pivot axis and at a relatively large radius therefrom and in sliding engagement with the contact edge of the said one potentiometer element, and electrical connections to the respective potentiometer elements, the angle between the contact edges of the said ele-

ments being adjustable by rotation of the cap relative to the housing.
